BUILDING CONSTRUCTION

Onnie Mankki, Cleveland Heights, Ohio, assignor
to Designers for Industry, Inc., Cleveland, Ohio,
a corporation of Ohio

Application January 9, 1945, Serial No. 572,002

2 Claims. (Cl. 20—4)

1

This invention relates to building construction and aims to provide a novel connection for panels or the like by which the meeting edges of adjacent panels are held in relatively tight engagement with each other.

Another object of the present invention is to provide an improved construction of this character, in which resiliently acting means embodied in the connection urges the edges of the panels toward a tight engagement which is constantly maintained regardless of expansion and contraction occurring in the panels.

A further object of the invention is to provide an improved connection for panels or the like of the kind having spaced side walls, and in which the connection embodies resiliently acting means engaging the panels at points adjacent the side walls thereof so as to urge the side walls of adjacent panels toward edgewise abutting engagement.

Still another object is to provide an improved connection of the character just mentioned, in which the contiguous edges of the panels have interfitting engagement.

The invention can be further briefly summarized as consisting in certain novel combinations and arrangements of parts hereinafter described and particularly set out in the appended claims.

In the accompanying sheet of drawings:

Fig. 1 is a face view showing building construction embodying the novel connection of the present invention;

Fig. 2 is a similar elevational view but showing the connection on a larger scale; and

Fig. 3 is a sectional view taken through the connection as indicated by line 3—3 of Fig. 1.

The novel construction of the present invention can be used to advantage in connecting various building units but is especially suitable for connecting prefabricated panels or the like which are frequently employed in walls, ceilings or partitions. In the drawing this novel connection is shown as being used for connecting the contiguous or meeting edges of a pair of adjacent units or panels 10 and 11, and utilizes connecting devices 21 which are described in detail hereinafter.

The panels shown in this instance are of the kind comprising a frame 12 and spaced side walls 13 and 14 connected to such frame. The frame

2

12 embodied in the panels 10 and 11 may be made of wood and as here shown comprises a plurality of spaced substantially parallel frame members or so-called stud members 15, such as 2 x 4's, which are suitably connected to other frame members 16 which may also be 2 x 4's and which extend at substantially right angles to the frame members 15. Along one pair of opposed edges of the panels 10 and 11 the frames 12 are provided with additional frame members 17 which may be in the form of 2 x 4's and which extend substantially parallel to the frame members 16 and are spaced from the latter and connected therewith through the blocks or spacers 18.

The side walls 13 and 14 of the panels 10 and 11 are in the form of sheets or plates which can be formed of any suitable material such as plywood, wall board, or the like, and are applied 20 against opposite sides of the frames 12 and secured to the latter as by means of nails or other fastening elements 19 extending through the sheets and into the frame members. As shown in Figs. 1 and 2, the sheets 13 and 14 preferably 25 do not extend over the frame members 17 and 18, the latter being left temporarily uncovered so as to provide the panels with spaces or openings 20 which afford access to the frame members and permit the installation of the connecting devices 21, which will be presently described 30 in detail and which are employed for connecting together the contiguous or meeting edges of adjacent panels.

As shown in the drawing, particularly Fig. 3, 35 the adjacent ends or edges of the panels 10 and 11 which are to be connected together are of a construction having novel cooperation with the connecting devices 21 as will now be described. As shown in the drawing, the frames 12 of the 40 panels 10 and 11 are provided with end members 23 and 24 which form an important part of the novel connection by which the adjacent edges of the panels are joined together. These end members are substantially parallel with the 45 frame members 15 and extend across the ends of the frame members 16 and have the ends of the frame members 17 connected therewith as shown in Figs. 1 and 2. The end member 23 is here shown as being a 1 x 4 and the end member 24 is here shown as being a 2 x 4. The edges 50

of the sheets or walls 13 and 14 of the panel 10 project beyond the end member 23 as a pair of spaced flanges 25 and 26. In the panel 11, the edges of the sheet walls 13 and 14 lie at or adjacent the mid-plane of the end member 24 so that a portion 27 of this end member, representing approximately one-half of the thickness thereof, projects beyond the edges of these walls.

When the panels 10 and 11 are assembled to form a wall, ceiling or partition they are placed in alignment with each other, as shown in the drawing, with the projecting portion 27 of the end member 24 of the panel 11 extending into the recess between the flanges 25 and 26 of the panel 10. The flanges 25 and 26 are made of a length such that their outer edges 30 will have abutting engagement with the corresponding outer edges 31 of the walls 13 and 14 of the panel 11 while the outer faces 32 and 33 of the end members 23 and 24 remain separated by the intervening space 34.

The connecting devices 21 serve to retain the adjacent panels 10 and 11 in the desired aligned relation and with their contiguous or meeting edges securely connected together in a manner such that the edges 30 and 31 of the panel walls will be resiliently held in abutting engagement with each other. The resilient action of the connecting devices 21 is very important because it causes the edges 30 and 31 of the panel walls to be constantly held in such abutting engagement so that a tight joint will be maintained between the contiguous edges of adjacent panels even though the panels may be later subject to expansion or contraction or even to a limited amount of misalignment or displacement. The connecting devices 21 are provided in suitable number for holding the panels in connected relation, and as mentioned above, can be readily installed in the panels through the spaces 20 provided therein. After the panels have been erected with the connecting devices 21 installed therein, the rows of spaces 20 can be closed or covered by trim boards or any other suitable material.

The connecting devices 21 may vary somewhat as to their details of construction, but as here shown, this connecting device comprises a pair of bowed resilient plates 36 and 37 and a connecting member in a form of a bolt or pin 38 extending through such plates and through the end members 23 and 24 of the panels. The resilient plates 36 and 37 are located inwardly of the respective end members 23 and 24 and engage the inner faces thereof. The bolt or pin 38 is provided with a nut 39 which is screwed onto this connecting member a distance sufficient to flex the plates 36 and 37 to thereby cause the latter to apply pressure to the end members of the panels in a direction for urging the edges 30 and 31 of the panel walls toward abutting engagement with each other.

Another important feature of this novel connection is that the bowed members 36 and 37 are disposed so that their ends 40 engage the inner faces of the end members of the panels at points immediately adjacent the side walls 13 and 14 as shown in Fig. 3. When the pressure of the bowed resilient plates 36 and 37 is applied to the panels at these points it acts more directly and effectively for urging the edges 30 and 31 of the panel walls into abutting engagement. It will be seen also that this construction and arrangement for the bowed plates 36 and 37 is less likely to result in distortion of the end members.

23 and 24 of the panels and these end members will be maintained more properly in alignment with each other so that there will be little or no tendency for the flanges 25 and 26 of the panel 10 to be pushed or wedged out of the planes of the outer faces of the panels. Moreover, it will be seen that the application of the pressure by the resilient plates in this manner tends to maintain the end member 24 in such position that it can have relative sliding movement between the flanges 25 and 26 without cramping or binding so that the work of installing the panels in proper alignment with each other and drawing their edges into interfitting and abutting engagement is greatly facilitated.

From the foregoing description and the accompanying drawing it will now be readily understood that the present invention provides building construction of an improved form in which a novel connection for prefabricated panels or units facilitates the installing and connecting of such panels in proper position and alignment, and produces a relatively tight joint between the contiguous edges of the adjacent panels which is constantly maintained even though expansion and contraction and a limited amount of misalignment or shifting may subsequently occur in the panels.

While I have illustrated and described the improved building construction and panel connection of the present invention in considerable detail, it will be understood of course that I do not wish to be correspondingly limited but regard my invention as including all changes and modifications coming within the scope of the appended claims.

Having thus described my invention, I claim:

1. In building construction, a pair of units each having an end member and a pair of spaced side walls disposed on opposite sides of and connected with such end member, said units being disposed in substantially aligned relation with edges of said side walls of one unit in abutting engagement with corresponding edges of the side walls of the other unit and with the outer faces of said end members adjacent to but spaced from each other, bowed resilient plates engaging the remote sides of said end members only at points closely adjacent said side walls, and a fastener extending through said end members and resilient plates for connecting the panels and holding said resilient plates in a flexed condition for urging said side walls of the two units toward said abutting engagement.
2. In building construction, a pair of units each having an end member and a pair of spaced side walls disposed on opposite sides of and connected with such end member, the side walls of one unit projecting beyond the outer face of its end member and the end member of the other unit projecting beyond the outer edges of its side walls, said units being disposed in contiguous relation with the projecting portion of the end member of said other unit engaging between the projecting portions of the side walls of said one unit and the projecting portions of the side walls of said one unit being of a length to abuttingly engage the edges of the side walls of said other unit and hold the end members of said units in spaced relation, bowed resilient plates engaging the remote sides of said end members only at points closely adjacent said side walls, and a fastener extending through said end members and resilient plates for connecting the panels and holding said resilient plates in a flexed condition.

for urging said side walls of the two units toward said abutting relation.

ONNIE MANKKI.
